CLAIM

The ornamental design for a curved dresser, as shown and described.

DESCRIPTION

FIG. 1 is a front perspective view of a first embodiment of a curved dresser showing our new design;
 FIG. 2 is a rear perspective view thereof;
 FIG. 3 is a front elevational view thereof;
 FIG. 4 is a rear elevational view thereof;
 FIG. 5 is a top plan view thereof;
 FIG. 6 is a bottom plan view thereof;
 FIG. 7 is a right elevational view thereof;
 FIG. 8 is a left elevational view thereof;
 FIG. 9 is a front perspective view of a second embodiment of a curved dresser showing our new design;
 FIG. 10 is a rear perspective view thereof;
 FIG. 11 is a front elevational view thereof;
 FIG. 12 is a rear elevational view thereof;
 FIG. 13 is a top plan view thereof;
 FIG. 14 is a bottom plan view thereof;
 FIG. 15 is a right elevational view thereof;
 FIG. 16 is a left elevational view thereof;
 FIG. 17 is a front perspective view of a third embodiment of a curved dresser showing our new design;
 FIG. 18 is a rear perspective view thereof;
 FIG. 19 is a front elevational view thereof;
 FIG. 20 is a rear elevational view thereof;
 FIG. 21 is a top plan view thereof;
 FIG. 22 is a bottom plan view thereof;
 FIG. 23 is a right elevational view thereof;
 FIG. 24 is a left elevational view thereof;
 FIG. 25 is a front perspective view of a fourth embodiment of a curved dresser showing our new design;
 FIG. 26 is a rear perspective view thereof;
 FIG. 27 is a front elevational view thereof;
 FIG. 28 is a rear elevational view thereof;
 FIG. 29 is a top plan view thereof;
 FIG. 30 is a bottom plan view thereof;
 FIG. 31 is a right elevational view thereof;
 FIG. 32 is a left elevational view thereof;
 FIG. 33 is a front perspective view of a fifth embodiment of a curved dresser showing our new design;
 FIG. 34 is a rear perspective view thereof;
 FIG. 35 is a front elevational view thereof;
 FIG. 36 is a rear elevational view thereof;
 FIG. 37 is a top plan view thereof;
 FIG. 38 is a bottom plan view thereof;
 FIG. 39 is a right elevational view thereof;
 FIG. 40 is a left elevational view thereof;
 FIG. 41 is a front perspective view of a sixth embodiment of a curved dresser showing our new design;
 FIG. 42 is a rear perspective view thereof;
 FIG. 43 is a front elevational view thereof;
 FIG. 44 is a rear elevational view thereof;
 FIG. 45 is a top plan view thereof;
 FIG. 46 is a bottom plan view thereof;
 FIG. 47 is a right elevational view thereof; and,
 FIG. 48 is a left elevational view thereof.
 The broken lines show portions of the curved dresser, which form no part of the claimed design.
